CONVERSION OF HYDROCARBONS

Filed Oct. 31, 1934

UNITED STATES PATENT OFFICE

2,072,805

CONVERSION OF HYDROCARBONS

Pike H. Sullivan, New Rochelle, N. Y., assignor to
Gasoline Products Company, Inc., Newark,
N. J., a corporation of Delaware

Application October 31, 1934, Serial No. 750,841

6 Claims. (Cl. 196—10)

This invention relates to the conversion of hydrocarbon oils into products suitable for motor fuel and pertains more particularly to a method of treating the lighter gaseous hydrocarbon products resulting from the cracking and distillation of petroleum oils.

One of the principal objects of my invention is to provide a method for treating the lighter gaseous hydrocarbons resulting from the cracking or distillation operation, which is more simple and effective than processes heretofore employed.

Another important object of my invention is to provide a method for treating lighter gaseous hydrocarbons, which can be carried out in more simple and compact equipment.

A further important object of my invention is to provide a process wherein crude petroleum oil may be converted into the maximum amount of motor fuel products having a high anti-knock value.

With the above and other objects in view, which will become apparent from a more detailed description hereinafter, the invention will be best understood by referring now to the accompanying drawing, which is a schematic illustration of an apparatus suitable for carrying my invention into effect.

Referring now to the drawing, the reference character 10, designates a heating furnace having a heating coil 11 into which fresh oil for the process may be introduced through line 12, provided with pump 13. This fresh oil may be from any suitable source, and is preferably a crude petroleum oil of paraffinic, asphaltic or mixed base character.

The oil upon passing through the heating coil 11 is heated to a distilling temperature for example in the neighborhood of from 550 to 700° F. The oil after passing through heating coil 11 is discharged through transfer line 14 into an intermediate section of a distilling and fractionating tower 15, wherein vapors and liquid products separate. The unvaporized products from the heating coil 11, together with heavy condensate formed in the intermediate zone 16 of the tower 15, are collected in trap-out tray 17, located below the point of entry of the fresh charge from heating coil 11 and are withdrawn therefrom through line 18.

The product withdrawn from the intermediate trap-out tray 17 is preferably passed by means of pump 19 to a second heating coil 21 located in the heating furnace 10 wherein it is subjected to mild conversion treatment for the purpose of

reducing the viscosity thereof without regard to the quantity or character of gasoline constituents which may be formed during the treatment. For example, the charge during its passage through the heating coil 21 may be heated to a temperature ranging from 750 to 850° F., for example, and maintained at this temperature for a period sufficient to convert a relatively high percentage of the original residual charge into gas oil constituents suitable for subsequent cracking under more drastic conditions. The charge passing through the coil is preferably maintained under substantial pressure. For example, the coil outlet pressure may range from 100 to 500 pounds per square inch.

The hot products, after being subjected to the viscosity breaking treatment within the heating coil 21 is passed through transfer line 22 provided with a pressure reducing valve 23, into the bottom section 24 of the distilling and fractionating tower 15 wherein vapors and heavy unvaporized residual products separate. The unvaporized residual products are withdrawn from the bottom of tower 15 through draw-off line 25 and may be rejected from the system. Vapors liberated in the bottom section 24 of tower 15 pass upwardly through a central vapor passage in trap-out tray 17 and are subjected to fractionation in the intermediate section 16 with the vapors from the fresh charge introduced through line 14.

Vapors remaining uncondensed in intermediate section 16 of tower 15 pass upwardly through a central vapor passage of another trap-out tray 26, positioned above the point of introduction of fresh charge through line 14, and are subjected to further fractionation in an upper intermediate section 27 of tower 15 to condense a heavier fraction thereof which is suitable for drastic cracking treatment. The temperature at the top of the upper intermediate section 27 is preferably controlled so as to condense hydrocarbons boiling substantially above the normal gasoline range.

Vapors remaining uncondensed in upper intermediate section 27 pass upwardly through another central vapor passage of another and higher trap-out tray 28 to the top fractionating zone 29 of the tower 15 wherein higher boiling gasoline constituents are condensed. For example the top of the tower 15 may be controlled to condense constituents boiling above 250—350° F.

The intermediate fraction collected in trap-out tray 28 is withdrawn from tower 15 through line 31 provided with pump 32, and is introduced into

a heating coil 33 located in furnace 34. This fraction upon being passed through the heating coil 33 is heated to a relatively high cracking temperature, so as to convert a high percentage 5 thereof into motor fuel constituents. For example, it may be heated to a temperature of from 900 to 1100° F. or more, and the oil may be maintained within the heating coil for a period sufficient to convert from 20 to 40 or more per cent 10 into gasoline constituents. The oil is preferably maintained at a relatively high pressure during the heating operation, such as, for example, from 500 to 1000 pounds per square inch. The cracked products from the heating coil 33 are passed 15 through line 35, provided with an indirect heat exchanger 36, into a separator 37, wherein residual liquid and vapor products separate.

Unvaporized residual products are withdrawn from the bottom of the separator 37 through 20 draw-off line 38, and are rejected from the system. Vapors liberated in the separator 37 pass overhead through line 39 to a fractionating tower 41, wherein the higher boiling hydrocarbons are condensed. The temperature at the top of 25 the tower 41 is controlled so as to retain the gasoline constituents in vapor form, and to condense the constituents boiling thereabove. For example, the temperature at the top of the fractionating tower 41 may be controlled so that 30 overhead vapor products have an end point of 400° F.

Vapors remaining uncondensed in the fractionating tower 41 pass overhead through line 42 to a condenser 43 wherein a final distillate product is liquefied. The products from the condenser 43 then pass to a receiving drum 44, wherein the gases and distillate separate. A final distillate product is withdrawn from the bottom of receiving drum 44, through line 45.

40 Gases remaining uncondensed in the condenser 43 pass overhead from receiving drum 44 through line 46 and are treated in a manner hereinafter described.

Because of the rather drastic cracking conditions maintained within the heating furnace 45 34, the gases withdrawn from the receiving drum 44 will contain a relatively large proportion of unsaturated constituents.

The higher boiling gasoline constituents 50 condensed in the upper end zone 29 of the tower 15 are withdrawn from trap-out tray 28 through line 47, and are passed to a separate reforming coil 48, located in furnace 49, wherein they are subjected to reforming treatment for the purpose 55 of improving the anti-knock properties thereof. This fraction during its passage through the heating coil 48 is preferably heated to a relatively high reforming temperature. For example, it may be heated to a temperature of the 60 order of 900 to 1200° F. The pressure within the heating coil 48 may be maintained relatively low ranging from atmospheric to 100 or 200 pounds per square inch.

The reformed products from the heating coil 65 48 pass through line 51, provided with an indirect heat exchanger 52, and are discharged into a separator 53, wherein liquid residue and vapor products separate. Unvaporized residual products are withdrawn from the bottom of the separator 70 53 through draw-off line 54 and are rejected from the system. Vapors liberated within the separator 53 pass overhead through line 55 to the fractionating tower 41 and are therein subjected to fractionation with the vapor products from the 75 separator 37. Condensate formed in the frac-

tionating tower 41 is withdrawn from the bottom thereof through line 56 and may be returned by means of line 57, and pump 58, to the inlet side of the heating coil 33, for further cracking treatment, or it may be withdrawn from the system through line 59 and subjected to separate cracking treatment if desired.

5 Vapors remaining uncondensed in the combined distilling and fractionating tower 15 pass overhead through line 61 to a condenser 62, wherein 10 gasoline constituents are liquefied. The liquid and uncondensed gases from the condenser 62 pass to a receiving drum 63 wherein gases and distillates separate. As before mentioned, in accordance with the preferred mode of operation, the higher boiling gasoline constituents will be 15 condensed in tower 15 and subjected to reforming treatment so that the distillate separated in the receiving drum 63 will comprise principally of the lower boiling gasoline constituents, in which 20 case they will be withdrawn from the receiving drum 63 through line 64 and 65 as a final distillate product.

25 However, it may be desired to subject the total gasoline fraction to a reforming treatment within the heating coil 48. In accordance with this latter mode of operation, the total gasoline constituents of the charge will pass overhead from the combined distilling and fractionating tower 15, 30 through line 61, and be condensed in the condenser coil 62. The distillate separated in the receiving drum 63 will then be passed through line 64 and 66 to the inlet side of the reforming coil 48. When operating in this manner, the trap-out tray 28, located in the top of the combined distilling and fractionating tower 15, may 35 be omitted.

35 The gases separated in the receiving drum 63 are withdrawn overhead therefrom through line 67. When relatively mild viscosity-breaking conditions 40 are maintained within the heating coil 21 located in the furnace 10 so that relatively small amounts of hydrogen and methane are formed during the viscosity-breaking treatment, it is 45 preferred to pass these gases through lines 67, 68 and pump 69 to a heating coil 70, located in furnace 71, wherein the gases are subjected to 50 pyrolytic conversion into unsaturated constituents. It may be preferred, however, particularly when more drastic viscosity-breaking conditions 55 are maintained within the heating coil 21, located in furnace 10, to pass these gases to an apparatus for removing the hydrogen and methane before 60 subjecting the same to pyrolytic conversion. In accordance with the latter procedure the gases from the receiving drum 63 pass through lines 67 and 72 into hydrogen and methane separating towers 73 and 74 wherein the gases are fractionated for removing the hydrogen and methane 65 therefrom as hereinafter described. The hydrogen and methane free gases removed from the top of the fractionating tower 74 through line 75 is returned, via line 76, to the inlet side of the heating coil 70 for conversion into unsaturated constituents. These gases may or may not be combined with other saturated gases from the system as hereinafter described.

70 As before mentioned, the heating furnace 71 is controlled to convert the saturated hydrocarbon gases into unsaturated compounds. For example, the gases during their passage through the heating coil 70 may be heated to a temperature ranging from 1100 to 1700° F. or higher, while maintained under relatively low pressure, ranging, for example, between atmospheric and 200 75

5 pounds per square inch. The gases are preferably subjected to a rapid heating while passing at a high velocity through the heating coil, and are maintained at conversion temperature for only a short period such as from one tenth of a second to a second. The velocity of the gases through the heating coil may be from 15 to 30 feet per second.

10 The gases after being subjected to the desired treatment within the heating furnace 70 are passed through line 77 and are combined in line 78 with gases from the reforming and cracking treatment before described. To this end the line 46 leading from receiving drum 44 and line 77 15 leading from heating coil 70 merge into line 78.

15 The gases resulting from the reforming and cracking treatment will normally contain substantial quantities of unsaturated constituents 20 which can be polymerized without being subjected to pyrolytic conversion.

25 The combined stream of gases in line 78 resulting from the gas-pyrolysis in the heating coil 70 and the cracking and reforming treatment in heating coils 33 and 48, respectively, may be passed, without further heating, directly to a polymerizing chamber 79 via lines 81, 82, 83, 84, pump 85 and lines 86 and 87, the temperature of the mixture ordinarily being sufficient owing to the heat derived from the hot products from coil 30 70. It may be desired, however, to subject these gases to further heating before carrying out the polymerizing reaction.

35 For example, the combined stream of gases may be passed through lines 78, 81, 82 and 88 to a heating coil 89 located in the separator 37, thence through line 91 to a second heat-exchange coil 92 located in the separator 53, thence through line 93 to heat exchanger 36 located in transfer line 35, thence through line 95 to heat exchanger 40 52 located in transfer line 51, thence through lines 96, 84, pump 85 and lines 86 and 87 to the polymerizing chamber 79. If desired, additional heat may be provided by passing the gases 45 through heating coil 97 located in a separate polymerizing furnace 98. Heat-exchange coils 89 and 92 and heat exchangers 36 and 52 are provided with by-pass lines 99, 101, 102 and 103, respectively, so that one or more of the heat exchangers may be by-passed if desired.

50 It is usually preferred, however, to subject the combined gases resulting from the pyrolytic conversion and from the cracking and reforming treatment to fractionation to remove the hydrogen and methane before subjecting the same to polymerization. In accordance with this latter procedure the combined gases from the line 78 is passed through line 104 provided with a heat-exchange coil 105 wherein the gases are cooled, 55 and then through line 106 provided with pump 107 to a fractionating tower 108.

60 The temperature and pressure conditions maintained within the fractionating tower 108 is controlled so as to condense all constituents boiling above methane and hydrogen. The uncondensed hydrogen and methane are withdrawn from the top of fractionating tower 108 through line 109. Separation of the hydrogen and methane may be aided by introducing a solvent or absorbent oil through line 111 into the top of the fractionating tower 108. This solvent oil may be a relatively heavy hydrocarbon oil such as condensate from the bottom of fractionating tower 41 or the intermediate fractions from trap-out trays 17, 26, and 28 of fractionating tower 15.

5 The condensate formed in the fractionating tower 108 and unvaporized solvent oil is withdrawn from the bottom of the tower through draw off line 112, and is introduced into an intermediate section of a second tower 113, wherein it is subjected to distillation and fractionation. A heating coil 114 is provided in the bottom of the tower 113 to supply additional heat for distillation. The tower 113 is heated to a temperature sufficient to distill the absorbed hydrocarbon gases from the solvent oil introduced into the tower 108 through line 111. The unvaporized solvent oil is withdrawn from the bottom of tower 113 through line 114, and again introduced through line 111 into the top of the tower 108. The hydrocarbon vapors liberated from the solvent oil in the fractionating tower 113 pass overhead through line 115, which connects with line 82 and are subjected to polymerization in chamber 79 after being heated to the desired polymerizing temperature in the heat exchangers 89, 92, 36 and 52, and/or the polymerizing furnace 98.

20 The gases before being passed to the polymerizing chamber 79 are preferably heated to a temperature of the order of 700 to 1000° F. and placed under a relatively high pressure, such as, for example, from 500 to 3000 lbs. per square inch.

25 The gases after being heated to the above mentioned temperature and placed under the desired pressure by the pump 85 are allowed to digest at the above mentioned temperatures and pressure for a period sufficient to polymerize the unsaturated constituents of the gases into higher boiling hydrocarbons suitable for motor fuel. For example, the gases may be allowed to digest in the polymerizing chamber 79 for from three to thirty minutes. If desired, a suitable polymerizing catalyst such as clay, may be introduced into the polymerizing chamber 79 to aid in the carrying out of polymerization.

30 The products from the polymerizing chamber 79, after being subjected to the desired amount of digestion therein, are passed through line 116, 35 provided with a reducing valve 117, into a combined fractionating and distilling tower 118, wherein liquid and vapor products separate. The fractionating tower 118 is maintained under a pressure materially below that maintained in the polymerizing chamber 79. For example, the pressure may be reduced to from 100 to 300 lbs. per square inch by the reducing valve 117. The higher boiling liquid polymers separated in the combined distilling and fractionating tower 118 40 are withdrawn from the bottom thereof through line 119 and may be rejected from the system, or may be passed to the heating coil 21, located in furnace 10 by a suitable line (not shown) and subjected to viscosity breaking treatment with the original charge in the manner hereinbefore described.

45 Vapors liberated in the bottom section of the tower 118 pass upwardly through a central vapor passage located in the trap-out tray 121, and are subjected to further fractionation in the upper section of the tower. The temperature of the upper section of the tower 118 is controlled to condense hydrocarbons boiling above the normal gasoline boiling range. For example, the overhead vapor products may have a 400° F. end point. The condensate fraction formed in the upper section of the tower 118 is collected in trap-out tray 121, and is withdrawn therefrom through line 122. This condensate fraction may be passed 50 55 60 65 70 75

through lines 122, 123, 57 and 31 to the cracking furnace 34, or it may be passed through lines 122, 124 and 18 to the viscosity breaking furnace coil 21.

5 Vapors remaining uncondensed in the fractionating and distilling tower 118 pass overhead through line 125 to a condenser 126, wherein a final distillate product is condensed. The products from the condenser coil 126 then pass to a 10 receiving drum 127, wherein the unpolymerized gases and liquid separate. The liquid is withdrawn as a final distillate through the line 128, and the gases may be removed over-head through line 129. The gases from line 129 may be then 15 passed to hydrogen and methane separating towers 73 and 74, which are operated in the same manner as towers 108 and 113 hereinbefore described. If desired, these gases may be rejected from the system through line 131 without further treatment. The gases freed of the hydrogen and methane in towers 73 and 74 are then passed 20 through line 76 to the gas pyrolysis furnace 71 for conversion into unsaturated compounds.

As illustrated, the gases from the receiving 25 drum 127 may or may not be admixed with gases from line 72 resulting from the stripping or viscosity breaking treatment, before being treated to remove the hydrogen and methane therefrom. In cases where it is desired to remove hydrogen 30 and methane resulting from the initial distilling and viscosity breaking treatment this removal can be advantageously effected in the same equipment used to remove hydrogen and methane from the final gases from receiving tank 127.

35 Although I have described my invention in connection with a specific apparatus, it will be understood that various other types of apparatus may be employed for carrying the invention into effect. For example, I have shown the 40 separate heating coils for heating desired hydrocarbon stocks located in separate heating furnaces, but it will be understood by those skilled in this art that a plurality of said heating coils may be positioned within a single furnace. For 45 simplicity, I have also shown the fractionating tower 15 and others provided with a plurality of trap-out trays for separating different fractions, with the understanding that these fractions may be collected by separate fractionation in separate 50 towers preferably arranged in series. It will be further understood that the temperature pressures and time of treatment are not limited to the specific values given herein.

55 While I have described the preferred embodiment for purposes of illustration, it will be understood that my invention embraces such other modifications and variations as come within the spirit and scope thereof, and it is not my intention to dedicate any novel features, or to unduly 60 limit the scope of my invention, except as necessary to distinguish from prior art.

I claim:

1. A process for converting hydrocarbon oil into 65 relatively low-boiling hydrocarbon oil suitable for use as motor fuel, which comprises distilling a crude petroleum and fractionating it to separate residual constituents and vapors, subjecting said residual constituents to a mild cracking temperature, separating the mildly cracked products into 70 tar and vapors, commingling said last-mentioned vapors with vapors from said distilling operation, fractionating the combined vapors to condense a clean condensate, subjecting said clean condensate to more drastic temperature conditions to crack the same, fractionating the cracked products into a cracked gasoline distillate, a gas fraction comprising principally hydrogen and methane, and an intermediate fraction substantially free from hydrogen and methane, subjecting said intermediate fraction to elevated temperature and superatmospheric pressure effective to polymerize constituents thereof to normally liquid products, fractionating the polymerized products to recover a motor fuel fraction and a heavier reflux, and delivering said reflux to one of the aforementioned cracking operations to crack the same.

5 Vapors remaining uncondensed in the fractionating and distilling tower 118 pass overhead through line 125 to a condenser 126, wherein a final distillate product is condensed. The products from the condenser coil 126 then pass to a 10 receiving drum 127, wherein the unpolymerized gases and liquid separate. The liquid is withdrawn as a final distillate through the line 128, and the gases may be removed over-head through line 129. The gases from line 129 may be then 15 passed to hydrogen and methane separating towers 73 and 74, which are operated in the same manner as towers 108 and 113 hereinbefore described. If desired, these gases may be rejected from the system through line 131 without further treatment. The gases freed of the hydrogen and methane in towers 73 and 74 are then passed 20 through line 76 to the gas pyrolysis furnace 71 for conversion into unsaturated compounds.

2. A process for converting hydrocarbon oil into relatively low-boiling hydrocarbon oil suitable for use as motor fuel, which comprises distilling a crude petroleum and fractionating it to separate residual constituents and vapors, subjecting said residual constituents to a mild cracking temperature, separating the mildly cracked products into tar and vapors, commingling said last-mentioned vapors with vapors from said distilling operation, fractionating the combined vapors to condense a clean condensate, subjecting said clean condensate to more drastic temperature conditions to crack the same, fractionating the cracked products to recover a cracked gasoline distillate, a gas fraction comprising principally hydrogen and methane, and an intermediate fraction substantially free from hydrogen and methane, subjecting said intermediate fraction to elevated temperature and superatmospheric pressure effective to polymerize constituents thereof to normally liquid products, fractionating the polymerized products to recover a motor fuel fraction and a heavier reflux, and commingling said reflux with said residual constituents for subjection to said mild cracking temperature.

3. A process for converting hydrocarbon oil into relatively low-boiling hydrocarbon oil suitable for use as motor fuel, which comprises distilling a crude petroleum and fractionating it to separate residual constituents and vapors, subjecting said residual constituents to a mild cracking temperature, separating the mildly cracked products into tar and vapors, commingling said last-mentioned vapors with vapors from said distilling operation, fractionating the combined vapors to condense a clean condensate, subjecting said clean condensate to more drastic temperature conditions to crack the same, fractionating the cracked products to recover a cracked gasoline distillate, a gas fraction comprising principally hydrogen and methane, and an intermediate fraction substantially free from hydrogen and methane, subjecting said intermediate fraction to elevated temperature and superatmospheric pressure effective to polymerize constituents thereof to normally liquid products, fractionating the polymerized products to recover a motor fuel fraction and a heavier reflux, and commingling said reflux with said clean condensate for subjection to said more drastic temperature conditions to crack the same.

4. A process for converting hydrocarbon oil into relatively low-boiling hydrocarbon oil suitable for use as motor fuel, which comprises distilling a crude petroleum to separate it into naphtha, a heavier clean condensate and residual constituents, subjecting said residual constituents to a mild cracking temperature under a high superatmospheric pressure, separating the products to recover gas, naphtha and a heavier clean condensate, subjecting said naphtha and said heavier clean condensate from said distilling and mild cracking operations to more drastic cracking

conditions, fractionating the products to separate cracked gases and distillate, collecting gases from the aforementioned operations, fractionating them to remove hydrogen and methane therefrom, subjecting the fractionated gases to elevated temperature and pressure adequate to effect a polymerization of constituents thereof to normally liquid products, fractionating the products to separate a motor fuel fraction and a heavier polymer fraction, and commingling said residual constituents for subjection to said mild cracking temperature.

5. A process for converting hydrocarbon oil in-
15 to relatively low-boiling hydrocarbon oil suitable for use as motor fuel, which comprises distilling a crude petroleum to separate it into naphtha, a heavier clean condensate and residual constituents, subjecting said residual constituents to a
20 mild cracking temperature under a high superatmospheric pressure, separating the products to recover gas, naphtha and a heavier clean condensate, subjecting said naphtha and said heavier clean condensate from said distilling and mild
25 cracking operations to more drastic cracking conditions, fractionating the products to separate cracked gases and distillate, collecting gases from the aforementioned operations, fractionating them to remove hydrogen and methane there-
30 from, subjecting the fractionated gases to ele-

vated temperature and pressure adequate to effect a polymerization of constituents thereof to normally liquid products, fractionating the products to separate a motor fuel fraction and a heavier polymer fraction, and delivering heavier polymer thus obtained to one of the aforementioned cracking operations to crack the same.

6. A process for converting hydrocarbon oil in-
10 to relatively low-boiling hydrocarbon oil suitable for use as motor fuel, which comprises subjecting heavy hydrocarbon oil to a mild cracking temperature, separating the mildly cracked products into tar and vapors, fractionating said vapors to condense a clean condensate, subjecting said clean condensate to more drastic temperature
15 conditions to crack the same, fractionating the cracked products to recover a cracked gasoline distillate, a gas fraction comprising principally hydrogen and methane, and an intermediate fraction substantially free from hydrogen and
20 methane, subjecting said intermediate fraction to elevated temperature and superatmospheric pressure effective to polymerize constituents thereof to normally liquid products, fractionating the polymerized products to recover a motor fuel fraction and a heavier reflux, and delivering said reflux to one of the aforementioned cracking operations to crack the same.

PIKE H. SULLIVAN. 30
